UNITED STATES PATENT OFFICE.

FREDRICK S. STAFFORD, OF CHICAGO, ILLINOIS, ASSIGNOR TO STAFFORD AUTO
LAMP & NUMBER COMPANY, OF CHICAGO, ILLINOIS, A CORPORATION OF TEXAS.

PLATE-RETAINING DEVICE.

1,135,144.

Specification of Letters Patent. Patented Apr. 13, 1915.

Application filed July 10, 1914. Serial No. 850,083.

To all whom it may concern:

Be it known that I, FREDRICK S. STAFFORD, a citizen of the United States, residing at Chicago, in the county of Cook and State of Illinois, have invented certain new and useful Improvements in Plate-Retaining Devices, of which the following is a specification.

My invention relates to a plate retaining device, and is concerned particularly with a retaining device for holding in position number plates used in connection with number display devices employed for automobiles.

It is the object of my invention to employ a device in which separate plates are used for each number, so that by using a single frame, and other parts associated therewith, any combination of numbers may be used in the same frame.

It is the particular object of my invention to so mount the separate number plates that resilient separating means are provided between adjacent plates, thereby effectually preventing any rattling of the plates during operation of the automobile.

These and other objects of my invention will be more readily understood by reference to the accompanying drawings, in which—

Figure 1 is a front elevation of a number display device, in which the illuminating lamp is combined with said device. Fig. 2 is a front elevation of a number pad, in connection with which my invention is used. Fig. 3 is a horizontal section taken on the line 3—3 of Fig. 1. Fig. 4 is a horizontal section taken on the line 4—4 of Fig. 2. Fig. 5 is a perspective and partial sectional view of one of the separators used in connection with my invention; and Fig. 6 is a vertical section on the line 6—6 of Fig. 1 on a reduced scale.

Referring first to the embodiment of my invention specifically illustrated in Figs. 1 and 3, the plate retaining frame consists of a hollow box-like structure, formed of sheet metal, having the back 10 and the front 11. A lamp 12 is mounted in the upper portion 45 of the frame, and the light from this lamp serves as illuminating means for the number plates 13, which are mounted in guideways 14, provided in the front 11 of the

device. As clearly indicated in Fig. 3, the sides of the device are closed by the side members 15 and 16 respectively. Fastened to the rear member 10 is the resilient abutment member 17, which projects forwardly and serves as a resilient abutment for the edge of the left-hand number plate 13.

Between adjacent number plates I provide the separators 18, which are most clearly shown in Fig. 5. Each of these separators consists of a front portion 19 and the channel-shaped members 20, which are adapted to receive the edges of the number plates 13. It will be apparent that if pressure is applied laterally to the number plates 13, the channel-shaped side members 20 are forced toward each other, and thereby afford resilient means for maintaining the number plates in position. At their ends the separators 18 have their front portions 19 cut away so that these ends may be readily slipped into the guideways 14 at the upper and lower ends of the plates 13. As clearly shown in Fig. 1, the right-hand plate 21 may contain the name of the State for which the automobile license number is issued, the year in which it was issued, or any other similar legends. A removable abutment slide 22 is inserted in a guideway 23, at the right-hand end of the number display device in order to securely hold the plates 13 and 21 in position.

In assembling the device which I have just described, the number plate shown at the left of Fig. 1 is first placed in position by inserting it at the right-hand end of the guideways 14. A separator 18 is next placed in position by turning the separator into an oblique position, placing its cut away ends in the guideways 14, and then turning it into a vertical position. Subsequent plates 13 and the plate 21 and additional separators 18 are next placed in position and the entire series of plates is then forced to the left against the resilient action of the abutment member 17 and the separators 18, so that the abutment slide 22 may be inserted in its guideway 23, thereby holding the entire series of plates in position so that rattling is effectually prevented during running of the automobile. Inasmuch as the plates 13 and 21 are preferably made of glass, it is important that danger

of breakage should be prevented, and this result is accomplished by reason of the resilient nature of the separators 18.

In the modification of my invention shown in Figs. 2 and 4, a sheet metal back 24 is provided and at its ends has the apertures 25, through which the bolts 26 pass in order to hold the abutment members 27 in position. At the upper and lower edges of the back 24 are provided the guideways 28, similar to the guideways 14 shown in Fig. 1. The plates 13 and 21 are held in position by the guideways 28 and are separated from each other by the separators 18, which are of exactly the same construction as the separators 18, shown in Figs. 1, 3 and 5. In assembling the numbers used in connection with the number pad shown in Fig. 2, one of the abutment members 27 is first fastened to the back 24. Plates 13 and 21 and the separators 18 are next placed in position. Finally the second abutment member 27 is fastened to the back 24, having been forced inwardly to a sufficient extent so that the side members 20 of the separators 18 are forced toward each other, thereby maintaining the latter under pressure.

It will be apparent to those skilled in the art, that many changes could be made in the detailed construction of the various parts which I have described without departing from the spirit or scope of my invention as set forth in the claims.

What I claim is:

1. In a plate retaining device, the combination of a frame having parallel guideways thereon, a plurality of plates engaging said guideways, abutment means at the ends of said series of plates, and resilient separators between adjacent plates, each of said separators comprising a front portion and

spaced side members adapted to be forced toward each other by lateral pressure, substantially as described.

2. In a plate retaining device, the combination of a frame having parallel guideways thereon, a plurality of plates engaging said guideways, abutment means at the ends of said series of plates, and resilient separators between adjacent plates, each of said separators comprising a front portion and channel-shaped side members normally separated from each other, but adapted to be forced toward each other by lateral pressure, substantially as described. 45

3. In a plate retaining device, the combination of a frame having parallel guideways thereon, a plurality of plates engaging said guideways, abutment means at the ends of said series of plates, and resilient separators between adjacent plates, each of said separators comprising a front portion and channel-shaped side members normally separated from each other, but adapted to be forced toward each other under lateral pressure, the front portion of said separator being removed at the ends of the latter, whereby the said ends may be inserted in said guideways, substantially as described. 60

4. In a plate retaining device, the combination of a frame having parallel guideways thereon, a plurality of plates engaging said guideways, a resilient abutment member at one end of said series of plates, resilient separators between said plates, and a removable abutment member at the opposite end of said series of plates, substantially as described. 70 75
